UNITED STATES PATENT OFFICE.

LEO J. GRUBMAN, OF BELLE HARBOR, NEW YORK.

EYE MOUNTING FOR DOLLS.

Application filed June 23, 1926. Serial No. 117,931.

This invention relates to eye mountings for dolls, and has for its primary object to provide an improved supporting and attaching means for the oscillatory eye members whereby said eye members when the mounting is arranged in the doll head may be relatively positioned in accordance with the spaced relation of the eye sockets or openings in the doll head wall, and which embodies suitable means automatically operating in the final act of attaching the mounting to the wall of the doll head whereby pressure upon the eye members will be relieved and said members permitted to recede out of excessive frictional contact with the walls of the eye openings or sockets. A device embodying this principle is disclosed in Patent No. 1,540,521, issued to me on March 23, 1925, and is broadly claimed in an application for re-issue of the said Letters Patent filed June 7, 1926, Serial No. 114,366.

It is the primary object and purpose of my present improvements to provide an eye mounting for dolls of the above character having certain novel features of construction which enable the mounting to be accurately applied within the doll head in proper location with respect to the eye receiving sockets in the wall thereof and securely attached to the head wall with ease and facility and without requiring the exercise of a high degree of skill.

It is a more particular object of the invention to provide an improved attaching means for the eye mounting embodying two similar members each having means at one of its ends to impale the wall of the doll head and said members being also provided with complementary parts automatically coacting with each other to rigidly lock said members in their applied positions.

It is another object of the invention to provide the attaching members with means for supporting the spaced eye members together with a gravity swinging element cooperating with the eye members to impart oscillatory movement thereto, and said attaching members also having means to coact with said element and hold the same and the eye members against a relative angular movement prior to the engagement of the attaching members with the wall of the doll head, and when so engaged to release said element and the eye members whereby they may move angularly with respect to each other and with relation to the attaching members, and thus

permit the eye members to recede out of close frictional contact with the doll head wall.

It is a further general object of the invention to provide such an eye mounting for dolls wherein the attaching means as well as the gravity swinging plate or element for oscillating the eye members are in the form of simple metal stampings, thus permitting of the production of such devices at relatively low cost.

With the above and other objects in view, the invention consists in the improved eye mounting for dolls, and in the form, construction and relative arrangement of its several parts, as will be hereinafter more fully described, illustrated in the accompanying drawings, and subsequently incorporated in the subjoined claims.

In the drawings, wherein I have disclosed one simple and practical embodiment of my present improvements and in which similar reference characters designate corresponding parts throughout the several views,

Figure 1 is a fragmentary vertical sectional view through a doll head taken substantially on the line 1—1 of Fig. 2, and showing one practical form of my invention attached thereto in its applied position;

Fig. 2 is a horizontal sectional view taken substantially on the line 2—2 of Fig. 1;

Fig. 3 is a view similar to Fig. 2, but showing the relative positions of the parts before the attaching members are engaged with the wall of the doll head;

Fig. 4 is a detail sectional view taken substantially on the line 4—4 of Fig. 3;

Fig. 5 is a vertical sectional view taken on the line 5—5 of Fig. 1, and

Fig. 6 is an enlarged detail vertical section taken on the line 6—6 of Fig. 3.

For the purpose of illustrating the manner of application of my improved eye mounting, in the accompanying drawings, I have shown a section of a doll head which may be molded or otherwise fashioned from wood pulp, papier-mâché or other suitable composition material. The front wall of this doll head is provided with the usual eye sockets indicated at 6 located in appropriate spaced relation to the other molded facial features of the doll head.

The new eye mounting forming the subject matter of the present application, in one practical form thereof includes two supporting and attaching members 7 of similar form and construction. Each of these members

preferably consists of a stamped sheet metal plate which, for the purpose of increasing its stiffness or rigidity longitudinally thereof is preferably of concavo-convex or curvilinear form on its transverse dimension as shown in Figs. 5 and 6 of the drawings. Each of these attaching members or plates at one of its ends is provided with a plurality of spaced teeth or prongs 8, which, as will more fully herein-
5 after appear are adapted to impale or be imbedded in the structure of the doll head. At its opposite end, the central part of each plate 7 is cut away as shown at 9 to provide the spaced longitudinally projecting fingers 10 and an arm 11 integrally connected with the central portion of said plate and bent to extend laterally at right angles thereto and from the convex side of the plate. The spaced fingers 10 are offset in relatively op-
10 posite directions from the planes of the re-
spective plates as indicated at 12 and are adapted for resilient overlapping engagement upon each other as clearly seen in Fig. 3 of the drawings.

15 In addition to the arms 11, each of the at-
taching plates 7 has a second arm 13 struck therefrom and projecting laterally from the same side of the plate as the arm 11 and in parallel relation to the latter. This arm 13 is provided on its opposite longitudinal edges with lugs 14, the purpose of which will be presently explained.

20 The ends of the arms 11 and 13 of the at-
taching members are apertured to receive a pivot rod or axis 15 which fits snugly in said openings but permits of a relative longitudi-
ninal movement of the attaching plates or mem-
bers 7 with respect thereto.

25 Upon the opposite ends of the rod 15, the eye members 16 are adapted to be engaged. As herein shown, each of these eye members is in the form of a substantially hemispherical shell of celluloid or other suitable material and the wall of this shell at diametrically op-
30 posite points and adjacent the rear open side thereof is provided with the openings 17 therin. These openings gradually taper or decrease in width towards their rear ends, and are of substantially triangular shape as shown. Thus, it will be understood that the eye members or shells may have a diametrical shifting movement with respect to the pivot rod or axis 15.

35 For the purpose of transmitting an oscil-
latory motion to the two eye members, I pro-
vide an elongated plate 18 horizontally positioned in substantially parallel relation with the two attaching plates 7 at the rear sides of the eye members 16. This plate has a central rectangular opening 19 therein through which the arms 11 of the two attaching plates forwardly project. From each end portion of the plate 18 a lug 20 is struck and is pro-
60 vided with an opening 21 therein of appre-
ciably greater diameter than the pivot rod 15

as seen in Fig. 6 of the drawings so as to loosely receive said rod and permit of a bodily movement of the plate 18 diametrically of said pivot rod. The openings formed by the outwardly struck lugs 20 in the plate 18 are vertically extended above and below said lugs as indicated at 22, such enlargement of said openings having a lengthwise dimension exceeding the maximum width of the arms 13 between the ends of the lugs 14 thereon.

75 The plate 18 is suitably weighted to cause a gravity swinging movement thereof, and for this purpose, I find it convenient to provide the lower edge of the plate 18 at its center with an angularly projecting ear or lug 23 to which one end of an arm 24 is connected by a rivet or other suitable means indicated at 25 frictionally holding the arm against casual pivotal movement but permitting said arm to be swung from the projecting position shown in Fig. 1 to a horizontal position in substantially parallel relation to the plate 18. The other end of the arm 24 is provided with a suitable weight 26.

80 Having above described the several structural parts of my improved eye mounting, the manner of assembling the same and attaching the mounting in applied position within the doll head will be readily understood from a comparison of Figs. 2 and 3 of the drawings. As shown in Figs. 3, 4 and 6, when the parts are first assembled, the offset fingers on the inner ends of the attaching plates 7 are slightly sprung from their normal positions and resiliently held in frictional overlapping engagement upon each other. In this position of said attaching plates, the lugs 14 on the arms 13 thereof are positioned against the rear face of the plate 18 inwardly of the vertically extended ends 22 of the openings in the end portions of said plate so that said plate is held against rearward movement relative to the pivot rod 15 and with its front side in contact with the rear edges of the eye shells 16 and the edges of the openings 17 in the walls of said shells in bearing engagement at their rear ends upon the periphery of said rod. Thus, it will be apparent that the several parts or elements composing the mounting are frictionally held or locked against relative movement. Nevertheless, it is of course, possible in initially positioning the mounting within the doll head to forcibly move the eye shells 16 relative to each other along the pivot rod 15 and with respect to the plate 18 as may be required in accordance with the spacing of the eye sockets in the wall of the doll head so that the peripheral surfaces of said shells will properly seat against the walls of said sockets or openings. After the proper relation between the eye members and the walls of the respective eye sockets has been obtained, the two attaching plates 7 are then separated and moved longitudinally in relative opposite directions

either by hand or by means of a suitable tool and the teeth or prongs 8 on the outer ends of said plates are simultaneously impaled or imbedded in opposite sides of the doll head wall. In this separation of the two attaching plates, the overlapping fingers 10 of course, frictionally slide upon each other and at the end of such movement when the prongs 8 are fully imbedded in the structure of the head wall, the end edges of said fingers come into alignment with each other and the fingers spring back to their normal positions so that the ends of the fingers are disposed in substantially the same plane and in abutting contact with each other, thus providing a rigid and unyielding locking means resisting any tendency of said attaching plates to move inwardly whereby the prongs 8 might become disengaged from the wall of the doll head. At the same time, or in other words, as the prongs 8 are thus impaled or imbedded within the wall of the doll head, the lugs 14 on the arms 13 move out of contact with the rear face of the plate 18 and into alignment with the extended ends 22 of the openings in said plate, thus releasing the pressure against said plate so that it may move rearwardly with respect to the pivot rod 15 towards the attaching plates 7 and out of contacting engagement with the rear edges of the eye shells 16. By thus relieving the pressure of said plates against the eye shells, the latter are also permitted to recede or move rearwardly on the pivot rod 15 by reason of the form of the opening 17 in the walls of said shells, and thus obviate excessive frictional contact of the peripheral surfaces of the eye shells upon the walls of the eye sockets 6. Thus, it will be apparent that thereafter these eye shells have a substantially free floating arrangement in the eye sockets of the doll head wall, and are maintained in non-positive operative relation with said sockets by the pivot rod 15 while the weighted plate or frame 18 constitutes the means for transmitting an oscillatory motion to the eye members. Thus, it will be seen that I have accomplished the fundamental object and purpose of my prior invention in a very simple construction and arrangement of the several essential elements which enables the mounting as a whole to be very quickly and accurately applied and securely attached in its operative position within the doll head while permitting of a maximum range of adjustment or flexibility between the spaced eye members to insure their free oscillating motion, regardless of such mechanical inaccuracies in the form and arrangement of the eye sockets as may reasonably be expected to occur.

In the above description, I have referred to a particular form of the attaching members 7 as well as a particular form of the oscillatory plate or frame 18. However, the detail features of these elements as herein re-

ferred to are not necessarily essential, and other equivalent mechanical means might be devised to subserve the purpose thereof. It is accordingly to be understood that in these particulars as well as in the form, construction and arrangement of the several other parts of the device, the essentials thereof might be exemplified in various other alternative mechanical structures, and I therefore, reserve the privilege of resorting to all such legitimate changes therein as may be fairly incorporated within the spirit and scope of the invention as claimed.

I claim:

1. Attaching means for oscillatory eye mountings for doll heads comprising two attaching members each having means to support the eye mounting in operative relation to spaced eye openings in the doll head wall and permitting the relative longitudinal movement of said members to their attached positions with respect to opposite sides of the head wall, and said members each having additional means automatically coacting to lock said members against movement from their attached positions.

2. Attaching means for oscillatory eye mountings for doll heads comprising two attaching members each having means to support the eye mounting in operative relation to spaced eye openings in the doll head wall and permitting the relative longitudinal movement of said members to their attached positions with respect to opposite sides of the head wall, and said members having slidably engaged portions automatically coacting with each other to lock said members against movement from their attached positions.

3. Attaching means for oscillatory eye mountings for doll heads comprising two attaching members each having means to support the eye mounting in operative relation to spaced eye openings in the doll head wall and permitting the relative longitudinal movement of said members to their attached positions with respect to opposite sides of the head wall, each of said members being formed at one end with means to impale the wall structure, and said members at their other ends having slidably engaged means automatically coacting with each other to lock said members against movement from their attached positions.

4. Attaching means for oscillatory eye mountings for doll heads comprising two attaching members each having means to support the eye mounting in operative relation to spaced eye openings in the doll head wall and permitting the relative longitudinal movement of said members to their attached positions with respect to opposite sides of the head wall, each of said members being formed at one end with means to impale the wall structure, and said members at their other ends having slidably engaged resiliently yieldable

portions automatically movable relative to each other into coacting relation to lock said members against movement from their attached positions when said members are im-
5 paled.

5. In combination, an eye mounting including spaced eye members and a gravity movable element for transmitting oscillatory motion to said eye members, said element and the eye members having means permitting of their relative angular movement with respect to the axis of oscillation, and relatively movable attaching members upon which the eye mounting is supported having means to coact
10 with said element and hold said element and the eye members against such relative angular movement, said attaching members adapted to be moved relative to each other and with respect to the eye mounting to their attached positions whereupon said means is disengaged from said element to permit of a relative angular movement between the eye members and said gravity movable element.

6. In combination, an eye mounting including spaced eye members and a gravity movable element for transmitting oscillatory motion to said eye members, said element and the eye members having means permitting of their relative angular movement with respect to the axis of oscillation, and relatively movable attaching members upon which the eye mounting is supported having means to coact
25 with said element and hold said element and the eye members against such relative angular movement, said attaching members adapted to be moved relative to each other and with respect to the eye mounting to their attached positions whereupon said means is disengaged from said element to permit of the angular movement of the eye members relative to said gravity movable element, and means for locking said attaching members against relative movement from their applied positions.

7. In combination, an oscillatory eye mounting for dolls including an axis and spaced eye members mounted on said axis having means permitting of angular movement of the eye members relative thereto, relatively movable attaching members having parts upon which said axis is supported, said members at one of their ends being provided with means for supporting engagement with the doll head wall, and means connected with the attaching members for holding said eye members against angular movement relative to said axis when the eye members are initially positioned in engagement with the walls of the eye sockets in the doll head, said means including coacting parts movable relatively to each other out of coacting relation as said members are moved to their applied positions to automatically release said eye members and permit of their angular movement relative to said means and with respect to the axis of oscillation of the eye mounting.

8. In combination, an oscillatory eye mounting for doll heads including an axis, spaced eye members and a gravity movable element to transmit oscillatory motion to said eye members each loosely mounted on said axis for angular movement with respect thereto, attaching means for the eye mounting comprising relatively movable members upon which said axis is supported, one of said members having means to cooperate with said element and hold the same and the eye members against such angular movement when the eye members are initially engaged with the walls of eye sockets in the doll head, said attaching members at one of their ends having means thereon to impale opposite sides of the doll head wall, and said first named means of said attaching members being moved out of cooperative engagement with said element as said members are relatively moved to their applied positions to thereby permit said element and the eye members to move in an angular direction relative to the axis whereby the eye members may recede out of excessive frictional contact with the socket walls.

9. In combination, an oscillatory eye mounting for doll heads including an axis, spaced eye members and a gravity movable element to transmit oscillatory motion to said eye members each loosely mounted on said axis for angular movement with respect thereto, attaching means for the eye mounting comprising relatively movable members upon which said axis is supported, one of said members having means to cooperate with said element and hold the same and the eye members against such angular movement when the eye members are initially engaged with the walls of eye sockets in the doll head, said attaching members at one of their ends having means thereon to impale opposite sides of the doll head wall, and said first named means of said attaching members being moved out of cooperative engagement with said element as said members are relatively moved to their applied positions to thereby permit said element and the eye members to move in an angular direction relative to the axis whereby the eye members may recede out of excessive frictional contact with the socket walls, and said members at their other ends having automatically coacting means to lock said members in their applied positions.

10. In combination, an oscillatory eye mounting for dolls including an axis, spaced eye members and a gravity movable element each loosely mounted on said axis for relative angular movement with respect thereto, two relatively movable attaching members each having arms in which said axis is supported, said members adapted for relative movement in opposite directions to their applied positions with respect to opposite sides

of the doll head wall, and certain of said arms having means cooperating with said gravity movable element to hold the same and the eye members against angular movement 5 in respect to the axis when the eye members are initially engaged with the walls of the eye sockets in the doll head, and moving out of such cooperative relation when said attaching members are relatively moved to 10 their applied positions to thus release the eye members for angular movement with respect to the axis whereby they may recede out of excessive frictional contact with the socket walls.

15 11. In combination, an oscillatory eye mounting for dolls including an axis, spaced eye members and a gravity movable element each loosely mounted on said axis for relative angular movement with respect thereto, 20 two relative movable attaching members each having arms in which said axis is supported, said members adapted for relative movement in opposite directions to their applied positions with respect to opposite sides of the doll 25 head wall, and certain of said arms having means cooperating with said gravity movable element to hold the same and the eye members against angular movement in respect to the axis when the eye members are initially 30 engaged with the walls of the eye sockets in the doll head, and moving out of such cooperative relation when said attaching mem-

bers are relatively moved to their applied positions to thus release the eye members for angular movement with respect to the 35 axis whereby they may recede out of excessive frictional contact with the socket walls, and said attaching members having integral slidably engaged portions automatically co-acting with each other to lock said members 40 against movement from their applied positions.

12. An eye mounting for dolls including spaced eye members, and gravity controlled means for transmitting oscillating motion to 45 said members about a relatively fixed axis, said members and means having means permitting of their angular movement with respect to said axis, and means for operatively supporting the mounting within a doll head 50 including a part coacting with said gravity controlled means to hold the eye members against such angular movement with respect to the axis when they are initially engaged in the eye sockets of the doll head wall, and 55 said part being movable out of engagement with said gravity controlled means in the application of the supporting means to the doll head to thereby release the eye members and gravity controlled means for angular 60 movement with relation to said axis.

In testimony that I claim the foregoing as my invention, I have signed my name hereto.

LEO J. GRUBMAN.
